EDUCATIONAL RULE

Nicholas Farinacci, Floral Park, N. Y.

Application May 13, 1952, Serial No. 19,703

Term of patent 14 years

(Cl. D25—1)

To all whom it may concern:

Be it known that I, Nicholas Farinacci, a citizen of the United States, residing at Floral Park, in the county of Queens and State of New York, have invented a new, original, and ornamental Design for an Educational Rule, of which the following is a specification, reference being had to the accompanying drawings, forming a part hereof.

Fig. 1 is a front perspective view of an educational rule, showing my new design; and

Fig. 2 is a rear perspective view thereof.

The dominant features of my new design are shown in solid lines in the drawing.

I claim:

The ornamental design for an educational rule, as shown and described.

NICHOLAS FARINACCI.
